United States Patent Office

Des. 227,562
Patented July 3, 1973

227,562

CASKET

William V. Pitt, P.O. Box 7622, Waco, Tex. 76710

Filed Nov. 1, 1971, Ser. No. 194,797

Term of patent 14 years

Int. Cl. D31

U.S. Cl. D19—1

FIG. 1

FIG. 2

FIG.3

FIG.4

FIG. 1 is a perspective view of a casket showing my new design;

FIG. 2 is a side elevational view thereof, the other (not shown) side being identical;

FIG. 3 is an end elevational view thereof, the other (not shown) end being identical;

FIG. 4 is an enlarged transverse vertical diagrammatic section.

I claim:

The ornamental design for a casket, as shown and described.
